EMERGENCY SHOWER HEAD

Edward S. McLean, Wilmington, Del., assignor to
Speakman CompanyFiled July 17, 1958, Ser. No. 749,160
7 Claims. (Cl. 239—439)

The present invention, which is an improvement over my prior Patent 2,303,478, relates to an improved shower head especially suitable for emergency use.

Emergency shower heads have been designed for the protection of personnel working in chemical laboratories, machine shops and other places of employment, where injury by either fire or chemicals is a possibility, and where it is necessary to have available an emergency shower that is capable of immediately delivering the largest possible volume of water.

Heretofore shower heads have been so designed as to deliver water from an inverted bell head. These heads have either had a face plate with perforations therein, which tend to become clogged, due to lack of use, or the face plate had an opening around the sides thereof which would not become clogged but which tended to give a hollow curtain of water. This is not the most satisfactory type of shower for emergency use. In order to overcome these difficulties the prior shower heads have been improved to give a shower having water curtains within the outer curtain so as to allow the user to obtain thorough soaking immediately upon operation of the shower.

It is an object of the present invention to provide an emergency shower head of the face member type having certain openings through this face member to allow control of the water within the curtain formed by the openings between the face member and the shower head body.

The many features of novelty which characterize this invention will be apparent from the description and claims annexed to and forming part of this specification. Reference should be had to the accompanying drawings and descriptive matter for a better understanding of the invention, in which is described and illustrated the preferred embodiment of the invention.

In the drawings:

FIG. 1 is a plan view of the shower head face member.
FIG. 2 is a side view of the shower head.

FIG. 3 is a sectional view on line 3—3 of FIG. 1.
FIG. 4 is a sectional view on line 4—4 of FIG. 5.

FIG. 5 is a plan view of an assembled shower head showing the face member of FIG. 1, mounted therein.

FIG. 6 is a plan view of a second modification of the shower head.

FIG. 7 is a side view of the modification shown in FIG. 6.

FIG. 8 is a sectional view on line 8—8 of FIG. 6.

FIG. 9 is a plan view showing a third modification of the shower head.

FIG. 10 is a side view of the modification shown in FIG. 9.

FIG. 11 is a sectional view on line 11—11 of FIG. 9.

FIG. 12 is a fourth modification, taken in section on line 12—12 of FIG. 13.

FIG. 13 is a plan view of the modification shown in FIG. 12.

The emergency shower head has an inverted bell shaped body 20 (shown in FIGS. 4 and 5) having a water inlet opening 21 in the upper end thereof and having a water outlet opening 22 in the lower or larger end thereof. Mounted across the water inlet is a spider 23 on which is mounted the face member 24 by means of the threaded stud 25 at the center thereof, this being locked in position by means of the screw 26 which is threaded into

2

the center of the stud 25. This face member 24 is adjustable to allow an opening 27 between the body 20 and the face member 24. The face member shown in detail in FIGS. 1, 2 and 3 has a series of angular vanes 28, 28 thereon. These vanes originate adjacent to the stud 25 and curve outwardly towards the periphery of the face member 24, and are machined down on the outer edges 29 (shown in FIG. 2). These vanes cause the water flowing therebetween to take a rotational motion. The vanes 28, 28 having the upper part 29 are in contact with the inside of the inverted bell shaped body 20 and having the openings 28a therebetween shown in FIG. 4. The face member 24 has circular grooves 30 and 31 cut therein. These grooves are cut through the face member but not through the vanes 28. The vanes will therefore hold the face member in assembly after the grooves have been cut. These grooves 30 and 31 (shown in FIG. 1) have sides 32 adjacent to the axis of the face member cut perpendicular, and opposite sides 33 cut on an angle to give a wider stream as shown in FIG. 3.

A second modification of this device is shown in FIGS. 6, 7 and 8, wherein the vanes have been omitted and the lugs 34, 34 are placed thereon so as to hold the face member in assembly when the grooves 35, 35 are cut therein. These grooves are made in the same manner as the grooves 30, 31 as shown in FIGS. 1, 2 and 3, and have the sides 36, 36 remote from the axis cut at an angle to the face member and the sides 37, 37 adjacent to the axis perpendicular to the face member.

A third modification, shown in FIGS. 9, 10 and 11 has short straight vanes 38, 38 on the upper surface of the face member, and tend to force the water outwardly in a circular motion. Grooves 39, 39 are cut radially in the face member to allow water to escape therethrough.

Another modification of this invention is shown in FIGS. 12 and 13, wherein the face member 40 is the same as that shown in FIGS. 1, 2 and 3 except that the circular grooves 30 and 31 are omitted, but the body portion 41 has the deflectors 42, 42 on the interior surface thereof. These deflectors are not arranged radially with respect to the body portion but are arranged at an angle so as to intercept the water discharged by the face member and deflect it inwardly.

In operation, the emergency shower, shown in FIG. 4, is assembled so that the opening 27 is a discharge port for the water. The source of water (not shown) is attached by means of a nipple or other connection (not shown) to the water inlet opening 21 and flows into the upper part of the body portion 20 behind the face member 24. It is discharged from this part of the shower head through the opening 27 along the interior surface of the lower part of the body portion. This water is given a swirling motion by the vanes 28 which tend to force the water against the inside surface of the lower part of the body portion. The circular grooves 30 and 31 discharge water within that portion flowing through the opening 27. This avoids the hollow curtain of water heretofore commonly found in emergency showers, as the water flowing through 30 and 31 discharges within the curtain flowing through the opening 27. In order to impart the swirling motion of the water discharged through 27, modifications of the vanes 28 are shown in FIGS. 9, 10 and 11, wherein the vanes 38 cause the same turbulent motion and the grooves 39 admit the water to the central part of the shower. The face member shown in FIGS. 6, 7 and 8 does not impart any turbulent motion to the water discharged but does have the grooves 35, 35 therein which admit water to the central portion of the shower.

The modification shown in FIGS. 12 and 13 has vanes 40a on the face member and also has deflectors 42, 42

in the lower part of the body portion. The water discharged through the opening between the face member and the body portion is discharged with a turbulent motion, where most of it will follow the flare in the lower part of the body 41, but some will be deflected inwardly as it strikes the deflectors 42, 42, which reverses this turbulence, and thereby forces the water inwardly towards the center of the shower.

The above description has defined a novel face plate and several modifications thereof. It has also defined a bell shaped body and a modification of this body comprising an addition thereto of water deflectors. Any of the face plates mentioned above may be used in any of the bell shaped bodies as these are all interchangeable.

While in accordance with the provisions of the statutes, there has been illustrated and described the best form of embodiment of this invention now known, it is apparent to those skilled in the art that changes may be made in the form of the apparatus disclosed, without departing from the spirit of the invention, which is only limited by the claims appended hereto.

What is claimed is:

1. A shower head comprising a bell-shaped body having water deflectors on the interior surface adjacent to the large diameter end of said body, an inlet for water opening to the interior of said body at the end of said body remote from said large diameter end, said water deflectors sloping so as to rotate the water towards the axis of said body, and a circular shower head face member mounted in and coaxial with said body and adjustable in the direction of the axis thereof to vary the width of the annular port space between the peripheral edge of said face member and the body portion, said face member having vanes on the upper side thereof to rotate the water during the discharge therefrom.

2. A shower head comprising a bell-shaped body having water deflectors on the interior surface adjacent to the large diameter end of said body, an inlet for water opening to the interior of said body at the end of said body remote from said large diameter end, said water deflectors sloping so as to rotate the water towards the axis of said body, and a circular shower head face member mounted in and coaxial with said body and adjustable in the direction of the axis thereof to vary the width of the annular port space between the peripheral edge of said face member and the body portion, said face member having vanes on the upper side thereof to rotate the water during the discharge therefrom, and grooves in the shower head face member to pass water therethrough.

3. A device as claimed in claim 2, wherein said grooves are circular and have a perpendicular side adjacent the axis, and the side remote from said axis being cut at an angle to the perpendicular.

4. A device as claimed in claim 2, wherein said grooves are radial.

5. A shower head comprising a bell-shaped body having water deflectors on the interior surface adjacent to the large diameter end of said body, an inlet for water opening to the interior of said body at the end of said body remote from said large diameter end, said water deflectors sloping so as to rotate the water towards

the axis of said body, and a circular shower head face member mounted in and coaxial with said body and adjustable in the direction of the axis thereof to vary the width of the annular port space between the peripheral edge of said face member and the body portion, said face member having curved vanes on the upper side thereof to rotate the water during the discharge therefrom, and circular grooves in the shower head face member having a perpendicular side adjacent the axis and the side remote from said axis being cut at an angle to the perpendicular.

6. A shower head comprising a bell shaped body having an inlet for water opening into the interior of said body at the end remote from the large diameter end thereof, said large end having a plane inner surface therein, and a stationary circular shower head face member mounted in and coaxial with said body and adjustable in the direction of the axis thereof to vary the width of an annular port space between the peripheral edge of said face member and the body portion, said face member having vanes on the upper side thereof to rotate the water during the discharge therefrom, and grooves in the shower head face member to pass water therethrough out the central portion of a water curtain.

7. A shower head comprising a bell shaped body having an inlet for water, opening into the interior of said body at the end remote from the large diameter end thereof, said large end having a plane inner surface therein, and a stationary circular shower head face member mounted in and coaxial with said body and adjustable in the direction of the axis thereof to vary the width of an annular port space between the peripheral edge of said face member and the body portion, said member having vanes on the upper side thereof to rotate the water during the discharge therefrom, and a circular groove in the shower head face member to pass water therethrough, said groove having a perpendicular side adjacent the axis and the side remote from said axis being cut at an angle to the perpendicular.
